UNITED STATES PATENT OFFICE

159,745

SCARF

Umberto Mauri, Moltrasio, Italy, assignor to Edgar C. Hyman Co., Inc., New York, N. Y., a corporation of New York

Application February 8, 1950, Serial No. 7,789

Term of patent 3½ years

(Cl. D3—12)

To all whom it may concern:

Be it known that I, Umberto Mauri, a citizen of the Republic of Italy and a resident of Moltrasio, Italy, have invented a new, original, and ornamental Design for a Scarf, of which the following is a specification, reference being had to the accompanying drawing, forming a part hereof.

the mid-point thereof, the whole showing my new design.

I claim:

The ornamental design for a scarf, substantially as shown and described.

UMBERTO MAURI.
